APPARATUS FOR RELIEVING CONSTIPATION

Arthur H. Warshaw, Kansas City, Mo.

Application September 21, 1939, Serial No. 295,933

1 Claim. (Cl. 4—237)

This invention relates to apparatus for relieving constipation and particularly the type thereof known as rectal stasis, and the primary object is the provision of means in the nature of a specially constructed toilet seat that will assist the occupant thereof in straightening the ano-rectal angle to such an extent as to facilitate evacuation and enable him to perform, with moderate straining power, the duty of emptying the contents of the descending colon, sigmoid and rectum.

This invention has for a further aim the provision of means for exerting a predetermined amount of pressure upon designated areas of the human body adjacent to the anal orifice whereby, upon application of rearward force on the part of the seated person, the angularity of the ano-rectal canal will be appreciably straightened as relaxation of the anal sphincters permit evacuation of material.

A yet further object of this invention is to provide a toilet seat having contact members thereon movable through vertical paths of travel and adjustable toward and from each other so that the occupant of the toilet seat may dispose the contact members in order that appropriate rearward movement imparted to the body will assist in accomplishing a complete evacuation.

Other objects of this invention, including specific details of construction and manner of embodying the concepts in operative devices, in the nature of those shown in the accompanying drawing, will appear during the course of the following specification. In the drawing:

Figure 1 is a top plan view of a toilet seat having apparatus for relieving constipation as a part thereof.

Fig. 2 is an inverted plan view of the same; and,

Fig. 3 is an enlarged detailed sectional view taken along line III—III of Fig. 2.

It has been found by extensive work that the ano-rectal canal is not a straight tube in the adult. The direction of the anal canal is downward and posteriorly. The angle formed is often nearly 45° with the horizontal and in many cases approaches an angle close to 30°.

According to authorities, two of the principal causes of rectal stasis, which this invention contemplates overcoming, are: (1) weakness of the voluntary muscles that assist defecation; and (2), neglect to respond to normal call which leads to distention and atony of the lower bowel. The first mentioned point is of the greatest im-

portance and is responsible for the large percentage of cases of rectal stasis.

I have found that a third cause is due to an abnormal acuteness of the ano-rectal angle. 5 Flabbiness of muscles, and particularly those of the abdomen, produce a condition which is an inability to exert a sufficient amount of intra-abdominal pressure to aid in intestinal evacuation. With this condition prevalent in most humans where an acute ano-rectal angle is found, the difficulties incident to evacuation are appreciably increased.

It is well known that the anus has some attachments to the skin and subcutaneous tissues. 15 and that backward pressure on the apparatus will cause anterior movement of the former. The amount of backward force imparted to the anatomy at the immediate area of the anal orifice may be governed by the occupant of the 20 toilet seat so that the acuteness of the ano-rectal angle is instantaneously changed to straighten the canal.

The first part of the angle of the ano-rectal canal may be straightened by exterior manipulation of that portion of the body adjacent thereto, and since it is the object of this invention to have means available to the user for assisting evacuation whenever seated upon the apparatus, embodying the concepts hereof, it has 25 been found desirable to construct a toilet seat as shown in the accompanying drawing.

In this drawing, the numeral 6 designates a normally horizontal seat having a hole 8 therethrough and conventional hinge structure 10, 35 through the medium of which, seat 6 is attached to bowl 12. The space between the upper edge of bowl 12 and the lower face of seat 6 is sufficient to receive hereinafter described parts of the apparatus, and the two contact members 40 indicated generally by the numeral 14, are adjustably mounted upon seat 6 so that the free edges exert a predetermined amount of pressure along each side of the anal orifice of the occupant.

45 These contact members comprise a rigid body element 16 having a covering of resilient material 18, the thickness at the inner, proximal edges of which is increased an appreciable extent so that the maximum contact at that portion of the body may be obtained.

Each contact member 14 is pivotally supported on pintle 20 that is journalled in bearings 22 secured to the underside of seat 6 through the medium of suitable elements 24. The hinge member per se is designated by the numeral 26

and the portion thereof joined to element 16 is provided with a slot 28 that receives bolts 30 so that members 14 may be moved toward and from each other. This adjustment is necessary but the amount of movement required is relatively small because the space between members 14 may be substantially the same for all persons.

Hinge 26 extends to each side of pintle 28 and that part opposite to the portion forming slot 28 has a head 32 thereon that rides in cam slot 34 formed in the annular side of drum 36. This drum is integral with worm gear 38 that is rotatably carried by screw 40. Worm 42 meshing with gear 38 is rigid to shaft 44 on the extended end of which is mounted a knob 46. Bearings 48 operably carry shaft 44 so that it may be turned about its axis by the occupant of seat 6. The position of knobs 46 is such as to render them easy to manipulate when the occupant is seated and shafts 44 may be individually or simultaneously rotated as desired for there is a knob on each side of the seat to permit the user to reach both knobs 46 at the same time desired.

When one of the knobs 46 is turned, drum 36 will travel about its vertical axis to move head 32 up or down as the case may be. Such action will force contact member 16 from the position shown in full lines of Fig. 3, for example, to the position shown in dotted lines thereof.

The location of contact members 14 should be well below the upper surface of seat 6 so that when the buttocks are positioned in hole 8, the major portion of the weight of the person will be carried by seat 6, while a predetermined amount of upward pressure is exerted by contact members 14.

When the individual occupies seat 6, both feet should be fixed firmly on the floor upon a rubber mat or the like, to prevent slipping. Rubber heeled or rubber soled shoes may be worn, and as the buttocks are moved backwards against the friction grip of contact members 14, normal straining should occur. The usual action caused by abdominal muscle strain, is a relaxation of the anal sphincters, and this normal function, coupled

with the tendency of the ano-rectal angle to straighten, due to backward pressure by the seat occupant, is conducive to easy evacuation.

The apparatus for relieving constipation which has been shown and described, has sound scientific and anatomical basis and case study has indicated the apparatus is useful in overcoming rectal stasis.

Obviously, toilet seats having physical characteristics other than those shown in the drawing may be made to embody the present invention and therefore, it is desired to be limited only by the scope of the appended claim.

Having thus described the invention, what is claimed as new and desired to be secured by Letters Patent is:

A toilet seat of the character described comprising a horizontal body having an oval hole therethrough; a pivotally mounted contact member disposed on the seat, in the hole thereof to one side of the major axis and near one end thereof to engage the occupant of the seat to one side of the anus thereof; and means for moving the contact member around its pivotal connection, said pivotal connection being spaced rearwardly of the anus of the occupant whereby upon movement of the contact member about the pivotal connection, upward and rearward pressure is exerted to straighten the ano-rectal canal of the seated occupant, said means for moving the contact member comprising a worm gear rotatably mounted on the seat, a gear in mesh with the worm gear, an operating shaft in connection with the worm gear extending to a point within reach of the seated occupant, a drum provided with a cam slot rigid with the gear, and a head on the contact member projecting into said slot whereby upon rotation of the gear and drum said contact member will be moved about the pivotal connection, the said contact member having a resilient covering thereon thicker along the innermost edge thereof than throughout the remaining portion.
